INVENTOR
ARTHUR F. VAN DYCK

BY *Frank Adams*
ATTORNEY

UNITED STATES PATENT OFFICE

ARTHUR F. VAN DYCK, OF YONKERS, NEW YORK, ASSIGNOR TO RADIO CORPORATION OF AMERICA, A CORPORATION OF DELAWARE

RADIO RECEIVING APPARATUS

Application filed November 7, 1925. Serial No. 67,475.

My invention relates to radio receiving apparatus of the vacuum tube type and particularly to supplementary current supplies therefore.

5 An object of my invention is to provide a multi-circuit connector means in combination with a portable radio apparatus and a plurality of alternative current sources.

Another object of my invention is to provide 10 a connector system adapted to connect, alternatively, portable sources of current, or non-portable sources of current, to a portable radio apparatus.

Another object of my invention is to provide 15 a multiple-circuit connector device having a prong member and plurality of socket members adapted to complete the circuits of a vacuum tube radio apparatus.

Another object of my invention is to provide 20 a connection system having a portable member and a stationary member respectively connected to portable and non-portable current sources and an interchangeable member connected to a portable radio apparatus.

25 It has been found possible to design radio receiving devices, preferably of the super-heterodyne type, which will function with a small loop antenna and which are sufficiently compact, so that the circuits, receiving

30 apparatus, translating device, and current supply sources may be mounted within a cabinet of such size and weight as to be conveniently portable. A typical apparatus of this kind embodies therein the super-heterodyne circuits, and triode vacuum tubes in such

35 type and number as to be conveniently energized by the provided 1½ volt "A" batteries, a "C" battery and four 2½ volt "B" batteries.

The requirement of portability, however, restricts both the number and size of the batteries incorporated in the apparatus and, therefore frequent renewal of the batteries becomes necessary when the apparatus is in regular use.

45 Since a portable set is frequently used for substantial periods of time in a fixed location, it has been found desirable to provide additional, alternative current sources for connection with the apparatus when it is in use in such a fixed location, for the purpose of

avoiding the drain upon the small sized batteries which are desirable in the portable case. This connection between the receiving circuits and the portable current sources or between the circuits and the non-portable sources must be one which is conveniently and easily made, otherwise the user will not take the trouble to change to the non-portable batteries when the set is returned from transportation to the stand. Also the connection means must be such that the user will not be able to connect the circuits wrongly, to the injury of the vacuum tubes.

55 This may be conveniently done by the apparatus of my invention which provides in the portable radio apparatus a set of small portable batteries connected to a socket connector means and cooperating plug member which in turn is connected to the radio receiving circuits. These members are conveniently contained within the portable case. A second socket member is provided, attached to the non-portable current sources, adapted to enter the portable case through an opening in the bottom thereof and to receive the 60 prongs of the second connector member. By this means, convenient interchange between the two sets of current sources is provided 65 and correctness of connection insured.

70 Other objects and structural details of my invention will be apparent from the following description when read in connection with the accompanying drawings, wherein:

75 Fig. 1 is a perspective view in rear elevation of the apparatus of my invention and,

80 Fig. 2 is a sectional view of the connector members of my invention.

85 In Fig. 1 a portable cabinet 1 contains the circuits, triodes and apparatus of a radio receiving system as disclosed by my copending application Serial No. 57,339, filed September 19, 1925. A stand cabinet 2 is provided containing the supplementary sources of current as shown by my copending application, Serial No. 67,474, filed November 7, 1925. In 90 Fig. 1 the "A" batteries 3 and a "C" battery are positioned upon the left hand side of the rear of the cabinet 1 and the "B" batteries 4 are positioned upon the right. Connections from these various batteries are brought to 95 100

a socket connection plate 5 in a predetermined sequence. A cable 6 contains the circuit wires to the radio circuits which are connected to a pronged connecting member 7 in a similar sequence. Another socket connector member 8 is provided and mounted upon the top of the stand cabinet 2. Connections are made from the sockets in the member 8 to the current sources contained in the cabinet 2 according to the previously mentioned disclosure. These connections are made in similar sequence to the connections to the socket plate 5.

This construction is better shown in sectional detail in Fig. 2 which shows the connection member 8 having an auxiliary plate 9 and prongs 11 which are connected to the wires 12 making up the cable 6.

Fig. 2 further shows the socket plate 8 and a sub-plate 14 in which are contained metal socket members 15 connected to wires 16 which lead to the current sources disclosed in the previously mentioned application.

In the operation of my device the radio apparatus may be brought to a portable condition by inserting the prong connector member 7 into the cooperating socket member 5. By this means the portable current sources 3 and 4 are connected to the radio receiving circuits and the apparatus becomes completely portable and may be caused to function while it is being transported.

When transportation is completed and the apparatus returned to a settled place it may be positioned upon the stand cabinet 2.

This operation inserts the socket connector plate 8 through an opening in the bottom of the cabinet 1 as shown. The prong connector plate 7 may then be removed from the socket connector member 5 and inserted within the socket plate 8 whereupon the batteries 3 and 4 are disconnected from service and current sources shown in the previously mentioned disclosure are connected. The apparatus then functions as a non-portable receiver.

The operation of inserting the connector member 7 within either the socket member 5 or the socket member 8 is a very simple procedure which is made such that improper connection is not possible and, therefore, correct polarities and potentials are applied from either set of current sources to the radio apparatus.

While I have shown but one embodiment of my invention in the foregoing drawings and descriptions it is capable of various modifications therefrom without departing from the spirit thereof, and it is desired therefore that only such limitations shall be imposed thereon as are required by the prior art or indicated by the appended claims.

I claim as my invention:

1. In combination, a portable cabinet including a radio apparatus, connector means comprising a single cable connected at one

end to the various circuits of said apparatus, a single plug member connected to the other end of said cable, a pair of socket members adapted to receive said plug member, independent current sources, either of said sources being adapted to energize all the circuits of the portable apparatus, connections between said socket members and sources of current, one of said sources of current being smaller than the other and mounted within said portable cabinet, a non-portable cabinet, said other current source being disposed within said non-portable cabinet, and means for facilitating selective connection of said plug member with the socket member connected to the larger current source when said portable cabinet is positioned against said non-portable cabinet.

2. In apparatus of the character described, a portable cabinet housing radio apparatus and a relatively small source of electrical energy adapted to energize all the circuits of the apparatus, a relatively non-portable cabinet housing a relatively large source of electrical energy adapted to energize all the circuits of the portable apparatus, connector means in the portable cabinet comprising a cable having at one end a connector member and connected at its other end to the radio apparatus in the portable cabinet at points where current is to be supplied thereto, a socket member attached to said portable cabinet for the reception of said connector member, connections from said socket member to the smaller source of electrical energy, a second socket member fixed to the non-portable cabinet for the alternate reception of said connector and connections from said second socket member to said larger source of electrical energy within the non-portable cabinet and means providing an aperture in the portable cabinet for receiving the second socket when the portable cabinet is positioned on the non-portable cabinet.

3. In combination, a relatively non-portable cabinet containing relatively large non-portable sources of current for a radio receiver, a socket member protruding from the top of said cabinet and connections from the current sources to the socket; and a portable cabinet containing radio receiving apparatus and relatively small portable current sources and having an opening in its base for the reception of the socket member when the portable cabinet is positioned on the top of the non-portable cabinet, another socket member fixed in the portable cabinet and a connector plug member having connections from it to the radio receiving apparatus for cooperation with either socket.

ARTHUR F. VAN DYCK.
